UNITED STATES PATENT OFFICE.

HERBERT E. IVES, OF MOUNT AIRY, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

PHOTOMETER.

1,086,535.

Specification of Letters Patent. Patented Feb. 10, 1914.

Application filed April 10, 1913. Serial No. 760,150.

To all whom it may concern:

Be it known that I, HERBERT E. IVES, a citizen of the United States, residing at Mount Airy, in the county of Philadelphia 5 and State of Pennsylvania, have invented certain new and useful Improvements in Photometers, of which the following is a specification.

The principal object of the present invention is to provide a hand photometer which can be conveniently used by lamp inspectors and others, for ascertaining the candle power of street lamps and the like.

Other objects of the invention will appear 15 from the following description which will be given in connection with the accompanying drawings, forming part hereof and illustrating one embodiment of the invention, and in which—

Figure 1, is a perspective view illustrating 20 a hand photometer embodying features of the invention and showing in a general way how it may be used. Fig. 2, is a top or plan view, partly in section, illustrating a 25 portion of a photometer embodying features of the invention, and Fig. 3, is a side view partly in section of the same.

In the drawings 1 is a staff adapted to be held in one hand with one end in contact 30 with a street light lantern or globe 2. This staff is graduated as at 3 and in the graduations account is taken of the distance between the end of the staff and the source of light 4 to be tested, or in other words, of 35 the distance between the light source 4 and the outside of the lantern or globe. The end of the staff is provided with a pad 5 which when present prevents slipping and avoids possible danger of breaking the glass of the 40 globe or lantern.

6, is a photometer box and it is slidable on the staff.

In connection with the photometer chosen for illustration in the accompanying drawings 45 7 is the standard light, 8 are translucent glasses and 9 is a silvered glass or other appropriate partition having a clear or unobstructed opening 10.

11 and 12 are handle members pivoted together at 13 and whereof one, 12, is connected with the photometer box. The other handle element 11 is provided with an end

14 which operates when released by reason of the spring 15 as a clutch to retain the photometer box 6 in any position to which it 55 may have been moved on the staff.

16 is a pointer on the photometer box which is used in connection with the scale for ascertaining the candle power of the 60 light source 4.

To light the standard light 6, which is an electric lamp, a storage battery 17 is provided. This battery is arranged to be carried, for example, in the pocket of the operator. In the circuit 18 of the battery there 65 is interposed a switch 19, one element of which is carried by the handle element 11 so that in the normal position of the handle element the circuit is broken and when the handle element is moved to take a reading 70 the circuit is made and the lamp lighted.

In use the operator may hold one end of the staff with one hand and place the other end of the staff against the lantern or globe of the street light. With his free hand the 75 operator presses the handle elements together thus establishing the circuit and releasing the clutch element 14, lighting the standard light 7 and freeing the photometer box on the staff. The operator may then 80 ascertain the candle power by comparison in the ordinary way and having done this, the operator releases the handle elements, thus breaking the circuit of the lamp 7 and locking the photometer box on the staff. 85 The operator at his convenience can then read the scale in respect to the pointer 16 and so ascertain the candle power.

The device as a whole is easily carried about and can be operated without making 90 any measurements or requiring any supports. Of course, it will be understood that the device is intended to be used at night and in the absence of such surrounding artificial light as would be disadvantageous. 95 These are conditions that render the device particularly useful for lamp inspectors, who by it can ascertain the condition of any street light accurately, quickly and without guesswork.

100 It will be obvious to those skilled in the art to which my invention relates that modifications may be made in details of construction and arrangement, and hence I do not

limit myself in regard to such matters or further than the prior state of the art may require, but

Having thus described the nature and objects of my invention, what I claim as new and desire to secure by Letters Patent is—

1. A hand photometer comprising the combination of a staff adapted to be held in one hand with one end in contact with a street light lantern and graduated with respect to the light in the lantern, a photometer box slideable on the staff, and means for retaining the box in any position in which it is put on the staff, whereby the box 15 can be operated by the other hand, substantially as described.

2. A hand photometer comprising the combination of a graduated staff, a photometer box slideable on the staff, a standard electric lamp and its portable battery and circuit, and means tending to lock the box and staff and break the circuit and adapted when released to make the circuit, substantially as described.

25 3. A hand photometer comprising the combination of a graduated staff, a photometer box slideable on the staff, fixed and movable handle elements, and a clutch ac-

tuated by said handle elements and adapted to clamp and unclamp the staff and box, substantially as described.

4. A hand photometer comprising the combination of a graduated staff, a photometer box slideable on the staff, a standard electric lamp and its portable battery and 35 circuit connections, and coöperating fixed and movable handle elements including an electric switch, and a locking device, substantially as described.

5. A hand photometer comprising the 40 combination of a staff graduated in respect to a lantern and the light therein and provided with a padded end, a photometer box provided with fixed and movable coöperating handle elements, a standard electric 45 light and its circuit connections and source of current, and a clutch and switch operated by the handle elements, substantially as described.

In testimony whereof I have hereunto 50 signed my name.

HERBERT E. IVES.
